UNITED STATES PATENT OFFICE

2,119,080

ELECTRIC SWITCH

Ernest C. Kennedy, Houston, Tex.

Application July 19, 1937, Serial No. 154,484

1 Claim. (Cl. 200—122)

This invention relates to electric switches and has for an object to provide a switch adapted to retain the circuit closed a brief predetermined interval of time after the switch has been opened so that one may retire or reach the switch of another room before the light actually becomes extinguished.

A further object is to provide a switch of this type having a novel resistance element for heating a thermostat arm, which curves outward and breaks the circuit at the end of a predetermined lapse of time after the switch has been opened.

A further object is to provide novel means for timing the switch so that a greater or less interval of time may lapse before the circuit is opened.

A further object is to provide a device of this type which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawings forming part 30 of this specification,

Figure 1 is a plan view of a switch constructed in accordance with the invention.

Figure 2 is a longitudinal sectional view taken on the line 2—2 of Figure 1 showing the switch in closed circuit position.

Figure 3 is a view similar to Figure 2 but showing the switch in open circuit position and the circuit held closed by the pivoted auxiliary contact on the switch blade and the thermostat controlled contact.

Figure 4 is a cross sectional view taken on the line 4—4 of Figure 1.

Figure 5 is a longitudinal sectional view taken on the line 5—5 of Figure 1 showing the thermostat controlled contact and the timing mechanism.

Figure 6 is a detail cross sectional view taken on the line 6—6 of Figure 5 showing the means for mounting the controlling spring of the thermostat operated contact to vary the tension of the spring.

Figure 7 is a detail perspective view of the guide bracket for the thermostat controlled contact.

Figure 8 is a detail perspective view of the

bracket for coupling the thermostat to the thermostat controlled contact.

Figure 9 is a plan view of the parts involved in bypassing the circuit around the blade and through the thermostat after the switch has been 5 opened.

Referring now to the drawings in which like characters of reference designate similar parts in the various views, 10 designates the switch receptacle, the same being formed as usual of insulating material. A bar 11 is secured to the receptacle and is terminally provided with openings 12 for the reception of screws or the like for mounting the switch in a conventional outlet box.

The main contacts of the switch, here shown 15 as a single pole structure, comprise a long contact 13 and a short contact 14, best shown in Figures 2 and 3. The contacts are anchored in the walls of the receptacle by brackets 8 which are equipped with binding post screws 16 which receive the line and load wires of the circuit.

The switch body 16 is provided with oppositely extending blades 17 and 18 and the blade 17 in both the open or the closed position of the switch engages the long contact 13. The switch is of the 25 snap type in the present embodiment controlled by a spring 18 and is limited in throw by spaced horns 20 engaging a stop pin 21 on the plate 11. A lever 22 projects through a suitable opening in the plate.

A bi-metallic lever arm 23, best shown in Figure 9, is fixed stationary at one end to the wall of the receptacle by a bolt 24 or other connector and secured to the other end of the arm is a resistance element 25 having a heating coil 26 35 sleeved loosely around the lever arm. An electrical conductor 27 is connected to one end of the coil and is connected to the short stationary main contact 14.

A channeled auxiliary contact 28 is pivoted 40 on the side of the blade 18 by a pivot pin 29 and a spring 30 is sleeved on the pin within the channel of the contact to hold the contact against accidental movement. The contact is provided with a lateral extension 31 which is adapted to extend 45 transversely across the lever arm 18, as best shown in Figure 9. When the switch is turned off, as best shown in Figure 3, the auxiliary contact engages a plunger 32, as best shown in Figure 3, which is slidably mounted in a guide bracket 33, best shown in Figure 7, and has an upturned end 34 which is confined in the bight of a U-shaped bracket 35, best shown in Figure 8. The bracket is riveted, as shown at 36 in Figure 5 to the projecting end 37, shown in Figure 9, 50

55

of the bi-metallic lever arm 23. An electrical conductor 38 connects the bracket with the end of the resistance coil. When the switch is turned off the current will be by-passed around the short 5 main contact 14 and may be traced through the conductor 27, resistance element 28, plunger 32, auxiliary switch contact 28 and switch blades 13 and 17 to the long switch contact 13 so that the circuit is maintained energized. After the switch 10 has been turned off for a predetermined period of time, the bi-metallic lever will be heated sufficiently to curve outwardly and withdraw the plunger 32 from engagement with the auxiliary contact 28 with the result that the circuit is 15 broken.

The period during which the plunger remains in engagement with the auxiliary contact is varied by means of a rotary screw 38 upon which a traveling sleeve 40 is threadedly engaged, as 20 best shown in Figure 6. The sleeve is provided with a wing 41 having an obliquely disposed slot 42 therein which slidably receives a spring 43 which is carried by an arm 44 that projects from the bracket 35 shown in Figure 8. As the tension 25 of the spring is increased by movement of the spring to one end of the slot the plunger 32 will be held to project further under the auxiliary contact 28 and thus increase the length of time during which the resistance element must 30 heat the bi-metallic lever arm, and vice versa.

From the above description it is thought that

the construction and operation of the invention will be fully understood without further explanation.

What is claimed is:

In an electric switch, fixed contacts one of which is longer than the other, a movable blade adapted to bridge the contacts and in any position engaging the long contact, a bi-metallic lever arm secured stationary at one end, a resistance element secured to the other end of the arm, a conductor extending from the arm to the short stationary contact, a spring pressed auxiliary contact pivotally mounted on the blade, a plunger connected to the bi-metallic arm and normally engaging said blade when the switch has been turned to the off position, the bi-metallic arm being heated and being adapted to curve outwardly and withdraw the plunger from engagement with the auxiliary contact to break the circuit at the end of a short lapse of time after the switch is turned to off position, a manually operable rotary screw, a tension spring secured at one end to the plunger, and a sleeve threadedly engaged with the screw and provided with a web having an inclined slot receiving the free end of the spring, rotation of the screw varying the tension of the spring to time the period during which the plunger remains in engagement with the auxiliary contact after the switch is turned to off position.

ERNEST C. KENNEDY.
